UNITED STATES PATENT OFFICE

ROBERT H. GAYLORD, OF LOS ANGELES, CALIFORNIA

ELEVATOR SIGNALING SYSTEM

Application filed May 20, 1925. Serial No. 31,555

This invention relates to an improvement in the type of elevator signaling system as described in the patent to James B. Smalley and Charles H. Reiners, No. 826,752, dated July 24, 1906. The main object of the invention is to provide selecting or intercontrolling means for both the signal circuits and the restoring circuits of a signaling system of this type so that only the first car of the installation to enter the signaling zone for a given floor will be enabled to cause operation of the signals and of the restoring means for that floor and direction of travel, to the exclusion of all other cars, thus preventing confusion in the signaling and also preventing a car which is not in control of the signal operation from operating the restoring means.

The feature of selection or intercontrol of the signal circuits and the means whereby such selection or intercontrol is accomplished are substantially the same as described in my patent application Ser. No. 700,604, filed March 20, 1924. The present invention contemplates the addition of certain devices to the system described in said patent application so as to selectively control the restoring circuits as well as the signal circuits and thus permit only the car which is in control of the signal circuits for a given floor to operate the corresponding restoring mechanism. In an elevator signal system provided with selective control means as described in said patent application, the first car of the installation which enters the zone for a certain floor at which a primary circuit closer or push button has been operated by an intending passenger assumes control of the signal circuits for that floor and direction of travel and causes its signals to be operated while preventing the operation of the signals for that floor and direction of travel for any other car in the installation. With the system described in said patent application the restoring circuits, whereby the signals for a given floor are cancelled and the signal circuits rendered inoperative of the zone for that floor, are not selectively controlled but remain in condition to be operated by any car passing out of such zone. As a result it is possible for a second car entering the signaling zone

for a floor for which the signals are under control of another car to pass through and out of said zone without the operator in said second car becoming aware that any signals are being given at that floor and to thus operate the restoring means to cancel the first car's signals. While means are provided in each car whereby the operator may if he desires open a break in his restoring circuit at the time of passing out of said signaling zone, the operator under the conditions above described, not being aware that another car was giving and receiving signals for that floor may pass out of the signaling zone without operation of the above described circuit opening means and thereby cause operation of the restoring means. This would cancel all of the signals for that floor and render the circuits therefor inoperative, the disadvantages of which in certain instances are readily apparent.

The principal object of the present invention is to eliminate the possibility of any such operation of the restoring means by a car which is not in control of the signal circuits, so that when one car has assumed control of the signal circuits it alone will be capable of causing operation of the restoring means, and the signals will therefore remain in operation until this car passes out of the zone, regardless of the movement of the other cars. Other objects and advantages of the invention will appear hereinafter.

The accompanying drawings illustrate embodiments of my invention and referring thereto:

Fig. 1 is a diagram showing the circuit connections and the selective control means for the signal circuits and for the restoring circuits for an elevator installation comprising two elevator cars.

Fig. 2 is a longitudinal view of a car-operated switch or commutator of the type shown in said patent to Smalley and Reiners.

Fig. 3 is a section on line 3—3 in Fig. 2.

Fig. 4 is a section on line 4—4 in Fig. 2.

Fig. 5 is a section of line 5—5 in Fig. 3.

Fig. 6 is a side elevation of the selective control means for the signal circuits for one floor and direction of travel.

Fig. 7 is a side elevation of the main sec-

ondary circuit controller for all the signal circuits for one floor and direction of travel.

Fig. 8 is a diagram of the main secondary circuit controller and the selective control means for one floor and direction of travel together with the circuits and parts of the system associated therewith.

Fig. 9 is a side elevation of a modified form of selective control means for the signal circuits and restoring circuits.

Fig. 10 is a view similar to Fig. 8 but with the type of selective control means shown in Fig. 9.

In Fig. 1 of the drawings I have illustrated diagrammatically the various parts of a signaling system according to my invention for an installation of two elevators indicated at 1 and 2. A suitable source of electricity for example an ordinary dynamo or generator is indicated at 5 although it will of course be understood that it will not in general be necessary to provide a special source of electricity as the same may be obtained by connecting the operating circuits to the public power lines. Each elevator car is provided with an electrically operated or controlled signal 6 which may for example be an electric lamp. Electrically operated or controlled signals may also be provided at the landings and adjacent the respective elevator shafts for signaling an intending passenger that a certain elevator car is approaching him in the direction which he desires to go. These signals are also preferably electric lamps and a series of the same, as indicated at 7 to 14, are preferably provided for each elevator car in the installation. In Fig. 1, the series of such signals nearest each elevator car corresponds to that car. The top and bottom floors are each provided with a single lamp for each elevator and each of the intermediate floors with a pair of lamps for each elevator such as 8 and 9 for the second floor. These will be usually located outside of the elevator shaft adjacent to each elevator doorway as is common at the present time, one of said lamps at each floor serving to indicate the approach of a downwardly moving car and the other the approach of an upwardly moving car.

Suitable manually operated primary circuit closing means such as ordinary push buttons are also provided at each floor by which the intending passenger by operating one of said circuit closing means will close or cause to be closed a break in the signal circuit for all the cars for the floor and direction of travel corresponding to such circuit closing means, thus placing said signal circuits in such condition that when any car-operated switch or commutator closes another break in the signal circuits of the corresponding car for that floor and direction of travel the proper signals will be operated. These manually operated circuit closing means at

the landings are indicated at 15 to 22 inclusive and constitute primary circuit closers, the top and bottom floors each being provided with one, and each intermediate floor being provided with two, of such primary circuit closers, the upper ones being to signal upwardly moving cars and the lower ones downwardly moving cars, as is customary in such devices. One side of each of said manual circuit closing means, for example, one of the contacts of each push button, in case such means are used, is connected to a suitable source of current, such as battery 24, and the other side of each of said manual circuit closing means is connected to a setting magnet adapted to control an electromagnetically operated circuit closing means corresponding to that floor and direction of travel, the circuit being completed from the other side of said setting magnet to the other side of battery 24 as hereinafter described. While only one set of push buttons is illustrated it will be understood that any desired number of such sets may be provided, for example, in a large installation there may be two or more push buttons at each landing for each direction of travel, arranged at convenient points adjacent the elevator shafts, all of said push buttons for one installation or one bank of elevator cars being cross-connected in the usual manner to the setting magnets for the same electro-magnetically controlled circuit closing means. These electro-magnetically controlled circuit closing means, indicated at 39 to 41 inclusive, constitute secondary circuit closers and will be described more in detail hereinafter.

A car operated switching device or commutator is provided for each elevator car and is operated by connection with said car in any suitable manner, the construction and operation of said switches being substantially the same as the construction and operation of the commutators described in said Smalley and Reiners patent with the exception that the switches shown herein are adapted for a five story or five landing signal system instead of for seven landings as shown in said Smalley and Reiners patent. The contacts and the electrical connections for the car-controlled switches are shown diagrammatically in Fig. 1 while the mechanical construction of such switches is shown more clearly in Figs. 2 to 5 inclusive. In Fig. 1 the contacts shown above each car belong to the corresponding car-controlled commutator. Each of these commutators is adapted to determine the time when the signals for the corresponding cars shall be operated, that is when the signal lights at the landing and in the car will be lighted up provided that a landing push button has been operated so as to close the other normally open break in the signal circuits. Each commutator consists of suitable fixed and relatively moving contacts and

in the present embodiment the brushes are indicated as constituting the moving members thereof, said brushes being arranged in two groups corresponding respectively to up and down travel of the car and adapted to contact respectively and alternately with two corresponding groups of fixed contacts arranged on opposite sides of the commutator. As shown in Figs. 2 to 5 each of said commutators may comprise a moving member or brush carrier 26 adapted to be moved back and forth by operation of the corresponding car, said moving member for example comprising a nut 27 which is adapted to work on a screw shaft 28 operated by connection with the car operating means in any suitable manner. Suitable means are provided for tilting said moving member on said shaft at each end of its path so as to shift the brush carrier so that one group of brushes is operatively engaged with the corresponding fixed contacts while the elevator car is travelling upwardly and the other group of brushes is operatively engaged with the other corresponding group of fixed contacts during the downward travel of the elevator car. Means for effecting this tilting operation may consist of a frictional bearing means as shown at 29 in Fig. 5 engaging screw shaft 28 whereby the nut 27 is caused to tend to turn or tilt one side or the other in correspondence with the direction of rotation of said screw shaft, and such means may further comprise a guide member 30 adapted to engage an arm 31 on nut 27 to hold the brush carrier tilted to one side while it is travelling in one direction and to the other side while it is travelling in the opposite direction all as set forth in the patent to Smalley and Reiners above referred to.

The group of fixed contacts in each commutator for the control of the "down" signals at the landings comprise two series of contact plates, one of such series being indicated at 33 to 35 inclusive and the other series being indicated at 36 to 38 inclusive. These two series of contacts are adapted to be engaged by the brushes as the car moves downwardly and it will be observed that each plate of the series 33 to 35 is connected to a "down" light; that is, contact plate 33 is connected to lamp 8, contact 34 to lamp 10, etc.

Contact plates 36 to 38 are connected to the corresponding electromagnetically controlled switches or secondary circuit closing means indicated as mercury pots 39 to 41 for control of the "down" signal circuits, each of which is provided with pivoted contact arm 42. Each of said connections from the contacts of the car operated switch to the mercury pots includes or passes through the corresponding selecting or intercontrolling devices hereinafter described. Said pivoted arms 42 for the mercury pots are operated by setting magnets 43 to 45 inclusive which are connected to and controlled by the respec-

tive "down" push buttons or primary circuit closers 16, 18, and 20. The pivoted contact arms are all electrically connected to one side of the dynamo or source of current 5.

The construction and arrangement of the mercury pots 39 to 41 together with the setting and restoring magnets for controlling the operation of the pivoted circuit closing arms 42 is shown in Figs. 7 and 8. Each setting magnet has an armature 46 adapted to control said contact arm 42. Said arm is normally held out of contact with the mercury in the mercury pot as shown in Fig. 7 by engagement of armature 46 with the other end of said arm as at 47 thereby causing a break in the signal circuits for the corresponding floor and direction of travel at this point. Upon energization of the setting magnet due to closing of the circuit at the corresponding push button, armature 46 will be attracted and contact arm 42 thereby released, permitting said arm to fall into the mercury pot and make contact with the mercury therein so as to close the circuit at this point. There is provided a restoring magnet as indicated at 48 to 50 for each of the contact arms 42 for restoring the same to the normal position as shown in Fig. 7 as the car starts to move away from the floor for which the signal has been operated, as will be described more in detail hereinafter.

It will be seen therefore that each intermediate floor, for the downward travel of the car, is served by one of said floor signal lamps such as 8, a contact plate of the car-operated switch such as 33 connected therewith, a contact plate such as 36 adapted to be electrically connected to said first-named plate as hereinafter described, said latter contact being connected to the source of electrical supply through an electromagnetically controlled switch means or secondary circuit closer such as 39 adapted to be operated by operation of a push button or primary circuit closer at the corresponding landing, and also through selecting or intercontrolling means for the signal circuits and for the restoring means, which will be described more in detail hereinafter. In order to control electrical connection between contact plates 33 and 36, 34, and 37, etc., there is provided a brush or brushes for each series of plates, as indicated at 51 and 52, these brushes being electrically connected as indicated. It will be obvious that when any one pair of these brushes engage the respective contact plates, for example contact plates 33 and 36 the corresponding floor lamp such as lamp 8 will be lighted up providing the other breaks in the circuit are closed. It is preferred to provide several pairs of these brushes 51 and 52 and space the pairs a distance apart less than the width of any single plate of the series so that each pair of corresponding plates such as 33 and 36 will be electrically connected while

the car is moving for several floors so that the floor light will light up several floors in advance of the cars and will remain lighted until the car reaches the floor, this arrangement of the brushes being shown diagrammatically in Fig. 1 and being also shown in Fig. 2.

The car signal circuits are also controlled by contact means in the car-operated commutator, comprising for example a long contact strip 54, electrically connected to the car signal in the corresponding car and thence to the source of electric power. There is provided one or more pairs of brushes 56 and 57, said brushes being electrically connected together and the brushes 56 being adapted to make contact with contact strip 54 and brushes 57 being adapted to make contact with the series of contacts 36 to 38. It is preferred to provide contact strip 54 and brushes 56 rather than to attach the circuit from the car lamp directly to brushes 57 but this construction may not be necessary in all cases. The car signal is therefore in circuit with brush means, such as brushes 57 adapted to engage the series of contacts 36 to 38. In the present embodiment these brushes 57 are shown as separate brushes from the brushes 51 and 52 aforesaid and this is the construction that is preferred but it will be observed as shown in Fig. 1 that when these brushes are in the position shown in that figure, one brush 57 rests on the same contact plate as a brush 52 and at that time said brushes are in effect a single brush. One purpose of separating said brushes however is to provide different periods of advance operation of the landing signals and car signals. For example in order to light up the car light only a floor or so before the car reaches the floor, brushes 56 and 57 are located behind the foremost brushes 51 and 52 so that the car light will not be lighted up until somewhat after the floor light is lighted. It is preferable to provide two or more pairs of the connected brushes 56 and 57 separated by a distance less than the width of each contact plate so as to maintain the car light in operation for the desired length of time.

Restoring means are also provided for automatically restoring the circuits to normal condition after an elevator car which is in control of the signals has passed by the floor at which the signals have been operated, such restoration of the circuits to normal condition being accomplished in this instance by opening the secondary circuit closer, that is, by raising the corresponding contact arm 42 out of its mercury pot such as 39. Such restoring means may comprise the restoring magnets 48 to 50 aforesaid, of which magnet 48 is shown in Fig. 7. Said electromagnet 48 will, when energized (subject to certain other conditions as hereinafter described), attract armature means 149 on contact arm 42 and

lift said arm out of the mercury pot 39 and cause the other end of said contact arm to be again brought underneath the end of armature 46 where it will be held until the setting magnet 43 is again energized. In order to energize the restoring magnets at the proper time there are provided a series of contacts 58 to 60 upon the car-operated switch or commutator. Brush 61 is adapted to engage said contacts and is connected in any suitable manner to battery 24 for example as shown by being electrically connected to a brush 62 engaging contact strip 63 which is electrically connected to said battery. The respective contact plates 58 to 60 are so positioned that when the car starts to move away from any floor at which the signals for that car have been operated, brush 61 will engage the corresponding one of said contacts and energize the corresponding restoring magnet so as to break the signal circuits at the secondary circuit closer as above set forth, such opening of the secondary circuit closer being also dependent according to my invention on certain other conditions as hereinafter described.

The brushes above mentioned have been shown in Fig. 1 in the relative positions they occupy as car 1 is descending, these brushes therefore controlling the car signal to said car during downwardly travel and the "down" signals at the landings for that car. The brushes are omitted from that part of the commutator of car 1 in Fig. 1 corresponding to the upward travel of the car, as such brushes are not in operative position at this time, being out of operative contact with the "up" plates on that side of the commutator. Contact plates and strips 65 to 75 are also provided however at the other side of the car-operated switch and are connected in the circuits and adapted to function during upward travel of the car in the same manner as the above described contacts function in the downward motion of the car. When the car moves upwardly the brushes for the "up" contact plates are shifted into such position by means operated by the car as shown in said Smalley and Reiners patent, so as to bring such brushes into position to engage the "up" contact plates 65 to 75 and thus control the "up" signals and the corresponding restoring magnets. This shifting of the brushes will be referred to hereinafter. The brushes for the "up" contact plates are similarly but oppositely arranged to those above described for the "down" contact plates. Said "up" brushes are indicated at 87 to 92 in Fig. 3 in inoperative position during downward movement of the car, said brushes being inoperative because of the fact that each connected pair of brushes such as 87 and 88, engage only one series of contact plates, such as the series 68 to 70. Mercury pots or secondary circuit closers 76 to 78, setting

magnets 79 to 81 and restoring magnets 82 to 84 are also provided for controlling the "up" signal circuits, all of said means being connected and adapted to function in a similar manner to those above set forth for the "down" signal circuits. The system is therefore provided with similar control means for upwardly and downwardly movement of the cars. It will also be understood that the car-controlled switching means for the other cars are also provided with similar contacts and brushes and are adapted to operate in the same manner as above indicated for car 1, only the contacts of such other devices being indicated, however, in Fig. 1.

A "night" signal or bell 85 may be included in the push button circuits, said bell being normally short-circuited through switch 86 and being adapted to operate upon closing a push-button only when said switch is open, for example, at night.

The above description of the signal system applies to all intermediate floors but in order to provide for operation of the signals at the top and bottom floors at the proper time it will be observed that the commutator contacts corresponding to each "down" signal at the top floor are located in the same series as those for the "up" signals for intermediate floors, while those for each "up" signal for the bottom floor are grouped with those for the "down" signals at intermediate floors. It will also be observed that in the normal operation of the elevators there is no need in the case of the top and bottom floors of the manually operated primary circuit closers nor of the electromagnetically operated secondary circuit closers controlled thereby. There are therefore no mercury pots for the signals at these floors nor any setting and restoring magnets nor restoring contact plates in the car-operated switches, such signals being adapted to always operate when a car enters the signal zone, subject however to the selecting or intercontrolling means hereinafter described. Push buttons 15 and 22 are however provided at the bottom and top floors respectively and are connected preferably through suitable resistance 93 to battery 24. These push buttons normally have no function but when the elevators are not in normal operation, for example, at night, switch 86 may be opened and, in such case, closing of any push button, including 15 and 22, will cause bell 85 to ring. These special provisions are also substantially the same as in the said Smalley and Reiners patent.

My invention comprises in connection with the above described signaling system, electrically operated selecting or intercontrolling means which are incorporated in the connections for the floor landing signals and car signals and preferably between the car-operated switches and the mercury pots or secondary circuit closers. A form of electromag-

netic selective control means for the signal circuits is shown in detail in Figs. 6 and 8. There is provided a set or series of such intercontrolling means for each floor and direction of travel and each set or series comprises a plurality of controlling electromagnets, there being one of such controlling electromagnets in each series for each elevator car in the installation. In Figs. 6 and 8 is shown a set of such devices comprising two controlling electromagnets 101 and 102 corresponding to the two elevator cars 1 and 2 in the above described installation. Said electromagnets are shown as mounted adjacent one another but this is not necessary since there is no mechanical interconnection between such devices, the same being connected only electrically, so that they may if desired be remotely separated from one another. In fact each of the electromagnetic devices 101 and 102 may be mounted adjacent the corresponding car-operated switch, and under certain conditions this method of installation may be advantageous. Each electromagnet controls an armature 100 carried by or attached to a pivoted arm 99 controlling a circuit breaker or controller. For this purpose said arm 99 may cooperate for example with a mercury pot 103 to control a branch circuit included in the car and landing signal circuits for the corresponding elevator car, as hereinafter described. Each electromagnet 101 and 102 may comprise two coils or windings 104 and 105 which in the form shown in Figs. 6 and 8 are wound on the same core and are connected in such a manner that when energized they act in opposition. In practice the two windings may be arranged as shown, or they may, if desired, each extend substantially the entire length of the electromagnet. The series of selecting devices shown at the left in Fig. 1 are for controlling the "up" signal circuits and those at the right for the "down" signal circuits, there being a set of such devices for the up signals for each floor except the top floor and a set of devices for the "down" signals for each floor except the bottom floor. Because of the arrangement of the contact plates in the car-operated switches as above set forth the set of intercontrolling devices for the down signals at the top floor are grouped in the diagram with the intercontrolling devices for the up signals at the intermediate floors and similarly the intercontrolling devices for the "up" signals at the bottom floor are grouped with the devices for the "down" signals at the intermediate floors. The coils or windings 104 for all the electromagnets of a given set are connected in series, for example by wires 107. A connection 106 leads from one of said coils to suitable electrically operated holding means such as electromagnet 142 adapted to control the restoration of the secondary cir- 130

cuit closer to normal position as hereinafter described, said electromagnet 142 being, in turn connected by wire 113, to the corresponding mercury pot or secondary circuit closer of the series 39 to 41 or 76 to 78, and connections 108 lead from the winding 104 of the electromagnet at the other end of the set to the several windings 105 of all the electromagnets in that set in parallel or multiple connection. From each coil or winding 105 a connection 109 leads to the corresponding pivoted arm 99 which establishes a contact with mercury pot 103 from which a wire 110 leads to the corresponding contact of the series 36 to 38 or 68 to 70 of the corresponding car-controlled switch.

Each of the secondary circuit-closers 39 to 41 and 76 to 78 may be provided according to my present invention with one of the above mentioned holding means 142, which may comprise an electromagnet located beneath the arm 42 of said circuit-closer and at the other side of the pivoted support of said arm from the corresponding restoring magnet such as 48, as shown in Figs. 7 and 8. The position of such electromagnet 142 is such that arm 42 when lowered to closed position, as in Fig. 8, rests upon the core 143 of said magnet, so that when said magnet is energized it holds said arm firmly in closed position and prevents it being opened by the restoring magnet until the holding magnet is de-energized. I have found it advantageous to separate the iron bracket 144 supporting the detent magnet 142 from the iron bracket 145 supporting the restoring magnet such as 48 by a layer or block of non-magnetic material, such as brass as indicated at 146, so as to prevent leakage of magnetic flux from magnet 48 through bracket 144, thus permitting the attraction of magnet 48 to act on arm 42 only on the proper side of the pivotal support thereof. It will be observed, Fig. 8, that the holding magnet 142 is connected in all of the signal circuits for the corresponding floor and is therefore adapted to be energized whenever any signal for that floor is in operation.

I also prefer to provide in connection with the above described system a car-operator's switch 111 in each elevator for cancelling or controlling the landing and car signals for that car and a car-operator's switch 112 for controlling the restoring circuits for that car, each of the elevator cars 1 and 2 being provided with one of each of these switches.

The signal circuits are as follows. From the dynamo 5 a wire 115 leads to branch wires 116 and 117, wires 116 being connected to the contact arms 42 of the secondary circuit closers for the down signal circuits and wire 117 being connected to contact arms 42 for the up signal circuits. From each mercury pot or from the other side of each secondary circuit closer a wire 113 leads to the corresponding

holding magnet 142. From the other end of said magnet a wire 106 leads to the corresponding set of selecting or intercontrolling electromagnets as above described and from each mercury pot 103 of each of said sets a wire 110 aforesaid leads to the proper contact 36 to 38 or 68 to 70 at the corresponding car-operated switch. From the contacts of the series 33 to 35 and 65 to 67 of each car-operated switch, wires 119 lead to the respective landing signals, those from the contact plates 33 to 35 leading to "down" signal lamps and those from contact plates 65 to 67 leading to "up" signal lamps. From said landing signals return connections 120 and 121 lead to the car-operator's signal control switch 111 in the corresponding car, from which connection 122 leads back to the other side of the dynamo 5. From the long contact strips 54 and 71 on both the "up" and "down" sides of the car-operated switch, wires 123 and 124 lead to the car signal 6 in the corresponding car, the other side of said car signal being connected, together with wire 121, to the car-operator's control switch 111. It will be seen therefore that by operating said control or signal-cancelling switch the return circuit for both the car signal and landing signals is interrupted.

The primary or manual control circuit leads by wire 125 connected to one side of battery 24 and wires 127 and 128 respectively to the setting magnets 43 to 45 and 79 to 81, from which wires 129 lead to the corresponding primary circuit closers or push buttons 16 to 21. The return circuit for said circuit closers is established by connections 130 and 131 to the other side of the battery 24.

The restoring circuit also leads by connection 126 and connections 127 and 128 to the restoring magnets 48 to 50 and 82 to 84, thence by wires 132 to the respective restoring circuit contacts 58 to 60 and 72 to 74 for all the car-operated switches in parallel, and from the long contact strips 63 and 75 of each car-operated switch by wire 133 to the restoring circuit switch 112 in the corresponding car. From said switches return wires 134 lead to the other side of battery 24. Opening of the restoring circuit switch 112 in any car therefore serves to open a break in all of the restoring circuits corresponding to that car so that such car in passing out of the signaling zone for any floor will not cause the restoring magnet to be energized and will therefore permit the corresponding secondary circuit closing means or mercury cup such as 39 to remain in closed or operative position.

The operation of the above described signaling system is as follows:

In normal or inactive condition assuming that none of the primary circuit closers or push buttons 15 to 22 at the landings have been operated by an intending passenger, the secondary circuit closers are all in open posi-

tion as in Fig. 7, that is to say the contact arms 42 for all the mercury cups 39 to 41 and 76 to 78 are held out of contact therewith as above described. The respective intercontrolling electro-magnets 101 and 102 are therefore deenergized and the armatures 100 thereof allow the contact arms 99 to rest in the mercury cups 103 and close the connection at this point, so that in normal condition all 10 of the circuit controllers or circuit opening devices of the selecting or intercontrolling means are in closed position. The signal circuits are not, however, completed since the complete establishment of any signal circuit 15 depends not only upon the closure of the corresponding contact arm 99 and mercury cup 103 of the intercontrolling means but also upon the closure of the circuit at the main secondary circuit closer or mercury cup 20 of the series 39 to 41 and 76 to 78 and also upon closure of a connection between the corresponding contacts of the car-operated switch.

Assuming that an intending passenger operates one of the push buttons, for example, the down push button 16 at the second floor, the corresponding control circuit as above described will be completed and the corresponding setting magnet 43 will therefore be energized, causing the corresponding contact arm 25 42 to drop into mercury cup 39 as shown in Fig. 1 and in Fig. 8 and close connection at the secondary circuit closer for the "down" signal circuits for the second floor for all the 30 cars. The first descending car which enters the signaling zone for that floor, for example, car 1 will then cause the break in the signal circuits at the corresponding car-operated switch to be closed by operation of the brush means as above described. The break in the 35 landing signal circuit will be closed first, by engagement of a pair of brushes 51 and 52 with contact plates 33 and 36 thus completing the signal circuit through the "down" landing signal 8 at the second floor for car 1. Current will then pass from dynamo 5 through wires 115 and 116 to contact arm 42 and mercury cup 39, thence by wire 113 to holding magnet 142, and through wire 103 to 40 the set of selecting or intercontrolling means corresponding to the "down" signals for the second floor. The electric current passes first in series by connections 107 through the coils or windings 104 of all the electromagnets 101 and 102 of that set and then passes through connection 108 to the other winding 105 of the electromagnet 101 corresponding to car 1. From said winding 105 the current passes through the corresponding connection 45 109 to contact arm 99 and mercury cup 103 and thence by the corresponding wire 110 to the "down" contact 36 for the second floor of the car-controlled switch corresponding to car 1. Since the circuit is closed at this point by brush means 51 and 52 in said car- 50 operated switch current will then flow through said brushes to contact plate 33 and thence to the corresponding "down" landing signal 8 at the second floor and through wires 120 and 121, switch 111, and wire 122, back 55 to the dynamo 5. Since the two windings 104 and 105 of each electromagnetic controlling device are wound so as to oppose each other upon energization thereof, the armature 100 of magnet 101 corresponding to car 1 remains unaffected because both windings thereof are energized, and the contact between means 99 and 103 of such device therefore remains closed. The "down" signal lamp 8 at the second floor will therefore be 60 lighted up, signifying to the intending passenger that car 1 is approaching that floor. In the case of the other electromagnetic inter-control device or devices such as 102 of the same set however only the coil 104 is energized, there being no connection established to the coil 105 of said device, so that the armature 100 thereof is attracted and the corresponding circuit is interrupted by breaking the connection between members 99 and 103 65 as indicated at 140 in Figs. 1, 6 and 8. An additional break is therefore established in the circuits of the "down" landing signals at the second floor for all the other cars except that which has assumed control of the signals 70 so that no "down" landing signal at the second floor for any other car can be operated as long as said first car remains in control of the signals, even though such other car comes within the signaling zone for that floor and thus causes the break in the circuit at the corresponding car-operated switch to be closed. It will be seen therefore that in any set of selecting or intercontrolling devices 75 the first device to operate, that is to say the first device through whose contact means 99 and 103 the current actually flows, remains in operative position and retains the connection closed at this point while opening such connection for all the other devices associated therewith and thereby rendering inoperative the signal circuits for the other cars for that 80 floor and direction of travel.

As car 1 approaches closer to the second floor, say when it is one floor or so away, a pair of brushes 56 and 57 will operate to close the circuit between contact strip 54 and contact plate 36 of the corresponding car-operated switch. Contact plate 36 being then in electrical connection with the dynamo through the secondary circuit closing means and the intercontrolling device as above described, current will flow through brushes 57 and 56, contact strip 54 and wires 123 and 124 to the car lamp 6 in car 1 and thence through switch 111 and wire 122 back to dynamo 5. Car signal lamp 6 is thus illuminated, signifying to the operator of car 1 that he is to stop at the second floor. Thus both the landing and car signals corresponding to 85 90 95 100 105 110 115 120 125 130

car 1 are operated while both of said signals for all other cars in the installation, such as car 2, are rendered inoperative by reason of a break in the circuits therefor at the corresponding intercontrolling device as indicated at 140. The above operation whereby the intercontrolling means selectively controls the signal circuits are substantially the same as described in my said patent application Serial No. 700,604. I will now describe the manner in which, according to the present invention, the restoring operation is also selectively controlled so that no car, other than that in control of the signaling operation, is capable of operating the restoring means.

In Fig. 8 the parts of the signal system associated with the "down" signals for the second floor are shown in the relative positions which they occupy when such signals are being controlled by car 1 as above described. It will be seen that the signal operating circuits include the holding magnet 142 associated with the corresponding secondary circuit closer or main mercury cup 39 and that as long as car 1 is in control of the signals, the arm 42 of secondary circuit closer will therefore be held in closed position. Thus even though car 2 should pass through the zone for the second floor in a downward direction and thus complete the restoring circuit at the car operated switch as indicated at 148 in said figure the resulting energization of the restoring magnet would be ineffective in opening the secondary circuit closer because of the holding effect of holding magnet 142. Any other car in the system may therefore pass through and out of the zone without causing operation of the restoring means. When car 1 is about to leave this signaling zone however brushes 61 and 62 come into position as indicated in Fig. 8 so as to close the connection in the corresponding restoring circuit and energize restoring magnet 48. Such completion of the restoring circuits is at first ineffective in operating the restoring means however for the reason above described. The brushes controlling the connections at the car-operated switch in the signaling circuit and in the restoring circuits are so positioned relatively that the connection is broken between the signal circuit segments somewhat later than the connection is completed in the restoring circuit. Thus it will be seen that with the brushes in the positions shown in Fig. 8 the connection is already completed in the restoring circuit but still remains closed also in the signal circuits so that the signals are in operation and the restoring means is prevented from operating. The direction of travel of the brushes in this diagram is represented as downward as indicated by the arrow adjacent brushes 56 and 57. As soon as the last of the pairs of brushes 51 and 52 and 56 and 57 pass out of engagement with the cor-

responding segments however the signal circuits will be interrupted and holding magnet 142 will be de-energized. Since the restoring magnet 48 at this time is in energized condition the restoring means will be immediately operated to break the connection at the secondary circuit closer. It will be observed that as soon as the signal circuits for car 1 are interrupted the circuit closing arm 99 of the intercontrolling devices for the other cars will be caused to drop and re-establish connection with the corresponding mercury cups 103, and if a connection should be established in this manner in the signal circuits for another car which was then in that zone before the circuit is broken at the secondary circuit closer as above described it will be seen that the signal circuits would be established for said other car and the holding magnet 142 re-energized and operation of the restoring means prevented. Such a contingency is prevented however by the fact that the motion of arm 42 to break the connection at the secondary circuit closer takes place much more rapidly than the motion of arm 99 to close connection at the intercontrolling means, since arm 42 is moved by the magnetic attraction of the restoring magnet 48 while the arm 99 is moved to closed position only by gravity. Furthermore, magnet 48 is already energized, and therefore acts instantaneously to move arm 42 to open position as soon as holding magnet 142 is de-energized. In this manner, when any car is in control of the signal in a certain zone, all the other cars are prevented not only from operating the signal in that zone but also from operating the restoring means therefor, while the first named car upon passing out of the zone is permitted to operate the restoring means simultaneously with cancellation of the signals. Furthermore the intercontrolling devices are at the same time restored to normal position and the entire system for that zone is thus restored to its original condition.

The operator of any car may, upon receiving a signal to stop at a certain floor, but not wanting to stop in answer to this signal, transfer the control of the signals for that floor to the next car by opening the signal circuit transfer switch 111 in his car. Not only the signal in such first car, but also the corresponding landing signal, will thus be canceled, and the intercontrolling means will all be restored to normal condition and the holding magnet 142 will be de-energized, while the contact will remain closed at the main secondary circuit closer for that floor, so that the next car to enter that signaling zone or any other car then in such zone will assume control of the signal circuits and will also assume control of the restoring means due to re-energization of holding magnet 142 upon such re-establishing of the signal circuits. The operator may, on the other hand,

open said transfer switch 111 at any time before or during the passage of his car through the signaling zone of a floor at which he does not wish to stop, before receiving a signal to 5 stop at that floor, and in that case his car will be prevented from establishing any signal circuits for that floor. Or, the operator after having stopped at a floor in response to a signal, may find that he cannot take on all 10 the waiting passengers, and in this case also he may open switch 111 and transfer the signals to the next car so that such next car will also stop at that floor.

It should be noted, however, that opening 15 of switch 111 alone in any car does not interrupt the corresponding restoring circuit so that if this switch alone were opened such car would cause operation of the restoring means upon leaving the signaling zone for 20 that floor, provided no other car had yet entered that zone and assumed control of the signal and restoring circuits, and would thus prevent the next car from receiving and giving the signals in the desired manner. It is 25 therefore desirable to provide another transfer or control switch 112 in each car and included in the restoring circuits as above described, so that the operator may, when opening 30 switch 111 for any of the above reasons, also open switch 112 and thereby open his restoring circuits and thus prevent operation of the restoring means when his car passes out of the zone. This ensures that the system will be left in proper condition so that 35 the next car to enter that signaling zone will assume control of the signals. Since it is generally desirable to open both of said transfer switches at the same time, I prefer in general to form said switches as a double-pole 40 switch, so that a single operation serves to open or close both the signal circuits and the restoring circuits simultaneously. Improper operation of the restoring means by a car which has released control of the signal circuits is thereby prevented.

The control of the restoring circuits so as to prevent operation of the restoring means by any car which is not in control of the signal circuits may be accomplished in other ways than that above described although such method is very advantageous for this purpose from the standpoint of simplicity and positiveness of operation. For example, the apparatus shown in Figs. 9 and 10 is adapted 50 to control the restoring circuits in a similar manner. In Fig. 10 I have shown diagrammatically the parts of the system and the circuits for only one floor and direction of travel, for example for the down signals for 55 the second floor. It will be understood however that the system is in this case provided with car-controlled switches adapted to control connections in the signal circuits and having contact segments as above described 60 corresponding to the different floors and di-

rection of travel, such contacts for the second floor down and the contact strips cooperating therewith being indicated at 33, 54, 58, and 63. Said car-controlled switches are also provided with brushes 51, 52, 56, 57, 61, and 62 70 adapted to control the connections between said contact segments and strips and thus control the signal and restoring circuits as above described. The system further comprises elevator cars 1 and 2, electric dynamo 75 or other source of electric power 5, car signals 6, landing signals such as 8, push buttons or primary circuit closers at the landings, such as 16, a battery or other source of electric power 24, and secondary circuit closers 80 on mercury cups such as 39. Each of said mercury cups is provided with contact arm 42 and the connection between said mercury cup and said contact arm is controlled by setting magnet such as 43 and restoring 85 magnet such as 48 as above described.

The intercontrol means used in this case are of somewhat different construction than above described and are adapted to directly 90 control circuit connections not only in the corresponding signal circuits but also in the corresponding restoring circuits. For example each of the intercontrolling devices 101 and 102 may comprise two separate and opposing electromagnets 104 and 105. Each 95 of said devices is further provided with a mercury cup 103 and contact arm 99, adapted to control a connection in the corresponding signal circuits, said arm being pivotally mounted at 150 so that gravity holds the arm 100 normally down in closed position within mercury cup 103. Said contact arm 99 is provided with armature means 100 between the two electromagnets 104 and 105 and adapted 105 to be attracted in opposite directions upon energization of one or the other of said magnets. Each intercontrol device also comprises another circuit closed such as mercury cup 151 and contact arm 152. Said contact 110 arm is pivotally mounted at 153 and is provided with counter-weight means 154 to normally hold said arm in open position. Contact arm 152 is also provided with armature means 155 adapted to be attracted by electromagnet 105 upon energization thereof so 115 as to move said contact arm to make contact with the mercury in mercury cup 151. In Fig. 9 the intercontrol devices for both the elevator cars are shown in normal position with the connection closed in the signal circuit and open in the restoring circuit. The system further comprises electrical connections 115, 106, 107, 108, 109, 110, 119, 120, 121, 122, 123, 124, 126, 127, 129, 130, and 131 substantially as above described with the exception 120 that wire 106 leads directly from the secondary circuit closer 39 to the intercontrol means, instead of through the holding magnet which is eliminated in this case. It will therefore be seen that all the electromagnets 125 130

104 of the intercontrol devices of each set are connected in series while the electromagnets 105 of such devices are connected in parallel substantially as in the first described form of the invention. The restoring circuit is somewhat different however and may comprise in addition to wires 126 and 127 and restoring magnet 48, wires 156 leading from the restoring magnet to the contact arms 152 of each of the intercontrolling devices in the corresponding set, wires 157 leading from the corresponding mercury cups 151 to the corresponding restoring circuit contact segments such as 58 at the car operated switches, and return wires 158 leading from the long contract strips 53 of the car-operated switches back to battery 24. It is therefore evident that when the contact arms 152 are in normal or open position as shown in Fig. 9 the corresponding restoring circuit is broken at this point and can only be established upon energization of the corresponding electromagnet 105. I also prefer to provide in this form of the invention a transfer switch 111 in each car and included in the corresponding signal circuits in the same manner and for the same purposes as above described, but as will appear hereinafter it is unnecessary in this form of the invention to provide any transfer switch in the cars and included in the restoring circuits, since the completion of any restoring circuit depends directly upon the completion of the corresponding signal circuit so that opening of the signal circuit transfer switch 111 will ensure the opening or the remaining open of the connection between circuit closing members 152 and 151 in the corresponding restoring circuit.

40 The operation of this form of the invention is as follows:

Assuming as before that an intending passenger has operated push button 16 at the second floor and for a downwardly moving car, setting magnet 43 is thereby energized and closes connection at the main secondary circuit closer 39. If now car 1 enters the signaling zone for the second floor down, the signal circuits will be completed first for the landing signals by means of brushes 51 and 52 and then for the car signal by means of brushes 56 and 57 so that both of said signals will be operated. The operation of the intercontrolling means upon completion of the signal circuits in this manner is as follows: Current passes from the secondary circuit closer 39 through wire 106 and then through all the electromagnets 104 of the corresponding set in series and then through electromagnet 105 of the intercontrol device 101 corresponding to car 1. From here the circuit is completed as before through contact arm 99, mercury cup 103 and wire 110 to the contact 36 of the car-operated switch for car 1, and hence through the car and landing sig-

nals. Both of the electromagnets 104 and 105 of the intercontrol device 101 are thus energized and since said electromagnets oppose each other the armature 100 is attracted equally in both directions and contact arm 99 still remains in closed position due to gravity. In the intercontrol device 102 on the other hand only the electromagnet 104 is energized, which therefore attracts armature 100 and moves contact arm 99 to open position, so as to break the connection in the signal circuits for the other car at this point. The operation of the intercontrol means as regards the signal circuits is therefore substantially the same as in the form first described. At the same time however energization of the electromagnet 105 of the intercontrol device 101 attracts armature 155 of contact arm 152 and throws said arm to closed position in mercury cup 151 so as to close a connection in the corresponding restoring circuit. Since the electromagnet 105 of the other intercontrol device or devices such as 102 in that set remains unenergized however, contact arm 152 of such other device or devices remains in open position so that none of the restoring circuits for the other cars can be completed. It is therefore evident that only car 1 can effect operation of the restoring means as long as it is in control of the signal circuits, even though another car, such as 2, should pass through and out of this signaling zone and thereby close its connection in the restoring circuit at the car-operated switch.

The restoring operation is in this case effected as soon as brush 61 comes into contact with segments 58 and thereby completes the restoring circuit through wires 126, 127, restoring magnet 48, wire 156, contact members 152 and 151 of the intercontrol device 101, wire 157, contact segment 58, brushes 61 and 62, contact strip 63, and wire 158 back to the battery 24. It should be noted that in this case the restoring operation should take place while brushes 51, 52, and 57 are still in engagement with contact segments 33 and 36 since the restoring circuit can only be completed while the signal circuit remains established. For this reason it is essential that brushes 61 and 62 should be so positioned relative to the other brushes that the connection is closed with contact segment 58 before the connection is broken by the contact segments 33 and 36. It may be pointed out as an advantage of this form of the invention that the actual breaking of the circuit during the restoring operation takes place in every case at the main mercury pot or secondary circuit closer such as 39 instead of between the brushes and contact segments of the car-operated switches as in the form above described. This may be of considerable advantage in some cases in preventing deterioration of the brushes or contact segments due to sparks or arcing which may result if the

connection is broken at this point. As soon as the restoring magnet 48 is energized as above described arm 42 will be moved to open position and all the signal circuits for that floor and direction of travel will be broken. The intercontrolling means will therefore be de-energized and all the contact arms 99 will be restored to closed position while the contact arm 152 of the restoring circuit which has just operated will be restored to normal or open position by counter-weight 154.

The operator of car 1 may as before cancel the signals and transfer the same to the next car or to another car in the zone 111 but it will be seen that there is no need of a second car-operator's transfer switch in the restoring circuit as in the form first described, since the opening of an established signal circuit for any car will automatically effect the opening of the connection between circuit closing members 152 and 151 in the corresponding restoring circuit, while the opening of transfer switch 111 by an operator before his signal circuits have been established, that is, in case he wishes to pass one or more floors without stopping, ensures that such connection between members 152 and 151 will remain open so that in either case operation of the restoring means by that car will be prevented. The elimination of the transfer switch in the car may be of advantage in some cases since it reduces the number of wires which must be connected to the car and may permit the use of a lighter cable for this purpose.

While the exact method of controlling the operation of the restoring means is somewhat different in the two forms of the invention, it is obvious that the result accomplished is substantially the same in any case, namely that when any car is in control of the signals for a certain floor all other cars are prevented from interfering with the signaling operation by operating the restoring means, while the controlling car is permitted to operate such restoring means upon passing out of the signaling zone. The means by which this is accomplished constitute in either case disabling means, since they disable the restoring circuits for all other cars from effecting the restoring operation. Such disabling means for each floor comprise, in the forms first described, the holding magnet 142 adapted to hold circuit closing arm 42 in closed position as long as any signal circuit remains established; in the second form such means comprise the circuit closing members 151 and 152, together with the electromagnet 105 controlling the same, said circuit-closing members being adapted to maintain an open break in all the restoring circuits except that corresponding to the signal circuit which is established. Other equivalent means might also be employed for this purpose, and my invention should therefore be understood to

include the use of any such means by which this result of selective control of the restoring means is accomplished. It will be seen that in both of the forms above described the armature portion 149 of each contact arm 42 and the corresponding restoring magnet such as 48 constitute restoring means adapted to move said contact arm so as to open the secondary circuit closer and thereby open all the signal circuits for that floor and direction of travel, and that means are also provided which are operable upon the establishing of any signal circuit to prevent effective operation of said restoring means by any restoring circuit corresponding to any other signal circuit.

What I claim is:—

1. In an elevator signal system for a plurality of cars, a plurality of signal circuits corresponding to the respective cars, a single restoring means adapted to open all of said circuits, a plurality of restoring circuits corresponding to the respective cars and all connected to said single restoring means to control the same, a plurality of switching devices corresponding to the respective cars and operating in synchronism therewith to control the corresponding signal and restoring circuits, and disabling means included in part in said signal circuits and operable to prevent control of said restoring means by a restoring circuit corresponding to any car, while a signal circuit corresponding to any other car is completed.

2. In an elevator signal system for a plurality of cars, a plurality of signal circuits corresponding to the respective cars, a single normally open circuit closer included in all of said circuits, manually operable means for causing a movement of said circuit closer to its closed position, a single means for restoring said circuit closer to open position, a plurality of restoring circuits corresponding to the respective cars and all connected to said single restoring means to control the same, a plurality of switching devices corresponding to the respective cars and operating in synchronism therewith to control the corresponding signal and restoring circuits, and means included in said signal circuits for disabling any switching device from so controlling the restoring circuit while any other switching device is in control of its signal circuit.

3. In an elevator signal system for a plurality of cars, a plurality of signal circuits corresponding to the respective cars, a single restoring means adapted to open all of said circuits, a plurality of restoring circuits corresponding to the respective signal circuits and all connected to said single restoring means to control the same, a plurality of switching devices corresponding to the respective cars and operating in synchronism therewith to control the respective

signal and restoring circuits, and disabling means included in said signal circuits and operable upon completion of any one of said signal circuits to prevent control of said restoring means by a restoring circuit corresponding to any other of said signal circuits.

4. In an elevator signal system, a construction as set forth in claim 3, each of said switching devices being adapted to maintain a closed connection in the corresponding restoring circuit at the time of opening the corresponding signal circuit, and thereby cause said restoring circuit to control the restoring means.

5. In an elevator signal system for a plurality of cars, a plurality of signal circuits corresponding to the respective cars, a single normally open circuit closer including in all of said circuits, means for closing said circuit closer, a single restoring means for restoring said circuit closer to open position, a plurality of restoring circuits corresponding to the respective signal circuits and all connected to said single restoring means to control the same, a plurality of switching devices corresponding to the respective cars and operating in synchronism therewith to control the corresponding signal and restoring circuits, circuit opening means included in the respective signal circuits and operable upon completion of a signal circuit corresponding to any one of said cars to prevent completion of a signal circuit corresponding to any other car, and normally inoperative disabling means included in said signal circuits and operable upon completion of said signal circuit corresponding to one of said cars to prevent control of said restoring means by a restoring circuit corresponding to any other signal circuit.

6. In an elevator signal system, a construction as set forth in claim 5, said disabling means being adapted to return to its normally inoperative condition upon subsequent opening of the completed signal circuit, and said construction comprising in addition a manually controlled circuit opening switch in each of said signal circuits.

7. In an elevator signal system for a plurality of cars, a plurality of signal circuits corresponding to the respective cars, a single normally open circuit closer included in all of said signal circuits, means for closing said circuit closer, a single electrically operated means for restoring said circuit closer to open position, a plurality of restoring circuits corresponding to the respective cars and all connected to said single restoring means to control the same, a plurality of switching devices corresponding to the respective cars and operating in synchronism therewith to establish and break the corresponding signal and restoring circuits, and a single electrically operated means included in all of said signal circuits and adapted, upon establish-

ment of any one of said signal circuits, to hold said circuit closer in closed position against the action of said restoring means.

8. In an elevator signal system, a construction as set forth in claim 7, each of said switching devices being adapted to maintain a closed connection in the corresponding restoring circuit at the time of breaking the connection in the corresponding signal circuit, so as to cause immediate operation of said restoring means upon de-energization of said holding means due to the breaking of said signal circuit.

9. In an elevator signal system for a plurality of cars, a plurality of signal circuits corresponding to the respective cars, a single restoring means adapted to open all of said circuits, a plurality of restoring circuits corresponding to the respective cars and connected to said restoring means to control the same, a plurality of switching devices corresponding to the respective cars and operating in synchronism therewith to control the corresponding signal and restoring circuits and thereby control the signaling and restoring operations, means included in said signal circuits for preventing any switching device from so controlling the signaling operation while any other switching device is in control of the signaling operation, and other means included in said signal circuits for preventing any switching device from so controlling the restoring operation while such other car-controlled device is in control of the signaling operation.

10. In an elevator signal system for a plurality of cars vertically movable to and from a plurality of landings, the combination of signals individual to each of said cars, circuits for said signals, switching devices connected to said circuits and operating in synchronism with the respective cars to cause operation of the signals corresponding to the respective cars as said cars approach one of said landings at which a stop is desired and contributing to the restoration of any operated signal to inoperative condition as any car leaves said landing, and means included in said circuits and operable to prevent the restoration of any operated signal by any car passing said landing unless such car is one whose switching device contributed to the operation of said signal.

11. In an elevator signal system for a plurality of cars vertically movable to and from a plurality of landings, the combination of signals individual to each of said cars to indicate a landing at which a stop is desired, circuits for said signals, means controlled from said landing for setting one of said circuits in signal operating condition, switching devices connected to said circuits and operating in synchronism with the respective cars to cause operation of the signal corresponding to respective cars in response

- to the operation of said signal setting means and contributing to the restoration of such signal setting means to inoperative condition as any car leaves said landing, and means included in said circuits operable to prevent the restoration of said signal setting means by any car passing said landing unless such car is one whose switching device contributed to the operation of said signal. 5
12. In an elevator signal system for a plurality of cars vertically movable to and from a plurality of landings, the combination of signals individual to each of said cars, circuits for said signals, switching devices operating in synchronism with the respective cars and defining signal zones for said landings, means controlled from said landings for setting said circuits in signal operating condition, means actuated by the switching device for the first car to enter a signal zone for a given landing after the operation of the signal setting means for such landing to cause operation of its individual signal, and contributing to the restoration of any operated signal to inoperative condition as any car leaves said signal zone, and means to prevent effective operation of said signal restoring means with respect to said given landing by the switching device corresponding to any car passing said landing unless such car is one whose switching device contributed to the operation of the signal for said landing. 20
13. In an elevator signal system for a plurality of cars, the combination of individual signals for the respective cars, circuits for said signals, switching devices operating in synchronism with the respective cars and defining signal zones for the landings, means controlled from said landings for setting said circuits in signal operating condition, means actuated by the switching device for the first car to enter a signal zone for a given landing after the operation of the signal setting means for said landing to contribute to the operation of the signal for such car, and tending to cause restoration of the signal setting means for said given landing to inoperative condition as any car leaves the zone corresponding to said landing, and means to prevent effective operation of said signal restoring means by the switching device corresponding to any car passing said landing unless such car is one whose switching device contributed to the operation of the signal for said landing. 45
14. In an elevator signal system for a plurality of cars, signal circuits individual to each of said cars, a plurality of switching devices connected to said circuits and operating in synchronism with the respective cars to establish the corresponding circuits as the cars approach a landing, circuit opening means also included in said circuits and operative, in response to the operation of
- any one of said switching devices to establish the corresponding signal circuit, to prevent establishment of the signal circuits for all the other cars for the same landing, means actuated by the switching devices for the respective cars and tending to open any established signal circuit as any car leaves said landing, and means included in said circuits and operable to prevent effective operation of said switching device actuated means by the switching device corresponding to any car while the signal circuit for any other car is established. 70
15. In an elevator signal system for a plurality of cars, signal circuits individual to each of said cars, a plurality of switching devices connected to said circuits and operating in synchronism with the respective cars to establish the corresponding circuits as the cars approach a landing, circuit opening means also included in said circuits and operative in response to the operation of any one of said switching devices to establish the corresponding signal circuits, to prevent establishment of the signal circuits for all the other cars for the same landing, means actuated by the switching devices for the respective cars and tending to open any established signal circuit as any car leaves said landing, and means included in said circuits and operable to prevent effective operation of said switching device actuated means while any signal circuit is established. 75
16. In an elevator signal system for a plurality of cars, the combination of stop signals individual to each of said cars to indicate a landing at which a stop is desired, circuits for said signals, means controlled from said landing for setting one of said circuits in signal operating condition, switching devices connected to said circuits, said switching devices being individual to each of said cars and each operating in synchronism with the associated car to cause subsequent operation of that car's signal in response to the operation of said signal setting means, said switching device tending to cause restoration of said signal setting means to inoperative condition as any car leaves said landing, and means included in said circuits and operable to prevent the restoration of said signal setting means by any car passing said landing unless such car is one whose switching device participated in the operation of said signal. 80
